H. R. Allen.

Straightening Club-Feet & Legs.

N° 73768

Patented Jan. 28, 1868.

United States Patent Office.

H. R. ALLEN, M. D., OF CHARLESTON, ILLINOIS.

Letters Patent No. 73,768, dated January 28, 1868.

APPARATUS FOR STRAIGHTENING CLUB-FEET AND CROOKED LEGS.

The Schedule referred to in these Letters Patent and making part of the same.

TO ALL WHOM IT MAY CONCERN:

Be it known that I, H. R. ALLEN, M. D., of Charleston, in the county of Coles, and State of Illinois, have invented a new and improved Apparatus for Straightening Deformed Limbs; and I do hereby declare that the following is a full, clear, and exact description thereof, which will enable those skilled in the art to make and use the same, reference being had to the accompanying drawings, forming part of this specification, in which—

Figure 1 is a perspective view of my improved apparatus from the outside.

Figure 2 is a perspective view of the same from the inner side.

Figure 3 is a plan view of the foot-plates.

Figure 4 is a transverse section of the foot-plates through the line $x x'$, fig. 3.

Figure 5 is a cross-section of the foot-plates through the line $y y'$, fig. 3.

Figure 6 is a detail section through the line $z z'$, fig. 1.

Figure 7 is a detail edge view of D D, fig. 1.

Figure 8 is a detail section through the line $w w'$, fig. 2.

Similar letters of reference indicate corresponding parts.

This invention refers to an apparatus for overcoming the deformity of the lower extremities, when such deformity consists in the abnormal flexion of one or both of the lower limbs, as in some forms of ankylosis and *talipes vulgaris*, (club-foot, so called.) It consists of a frame provided with straps to retain the limb firmly within it, and further providing the said frame with joints for flexing the same to fit the limb, together with springs for exerting a continual straightening-tension, and other devices perfecting the whole, as will be herein-after more fully set forth.

In the drawings, A is the upper frame-plate, having a curved brace, B, riveted firmly thereto in the manner shown, for the purpose of providing a hollow frame of suitable size and form for the reception of the upper part of the human leg. C is the lower frame, having curved braces D D' for the reception of the lower part of the limb. These two frames are pivoted together by stout rivets $a a'$, which permit the frames to be accommodated to the flexed position of the limb to be treated.

Straps E, F, and G, buttoned or buckled as shown, confine the limb firmly within the aforesaid frames. H is a longer or elastic strap, attached to the upper part of the frame A by a rivet-button similar to the straps E and F, but for another purpose, as will be hereinafter described.

I and J are the foot-plates. To the foot-plate J are riveted the side-plates K, by which the foot-plate J is pivoted to the lower frame C by stout rivets, as shown at b, thus permitting the foot-plates to be turned downward when applying the apparatus to the limb, and the movement of the foot when the frame is so applied. This movement also serves a purpose in connection with its spring-attachments, all of which will be duly set forth. The foot-plate J is further provided with two lateral bearing-plates, L and M, which are riveted to the soles of the foot-plates, and are curved to conform somewhat to the natural curvature of the foot at the point of contact with the same. These plates have a partial movement on their rivets, c, so that they will adjust themselves to the foot when pressed against it. The foot-plate I is formed with an extension, d, as shown, and is pivoted by a stout rivet, e, to the plate J, so that the plate I is provided with a lateral movement for a purpose to be shown. The plate I has two movable side-plates, N and O, which are curved to conform to the foot, and one of these plates is, like the plates L and M, self-adjusting, and for bearing against the side of the foot, in a manner to be described.

The foot-plates I and J are also connected laterally by means of a spring-attachment shown at figs. 1, 3, and 4. It consists of a wire, f, rubber springs, g, washers, h, and burr, i. This wire rests in holes through the shoulder-lugs k, against which latter the springs g abut, when their tension is exerted by screwing up the burr i. Slots j in the plate J permit the passage of the strap G. A metallic strap, P, is riveted to the side-plates K, as shown, and terminates in links l for the passage of the foot-strap G, as will be more fully described.

To provide the proper vertical tension to the foot-plates, spring-attachments on each side of the frame, and about in the region of the ankle-joint, as shown in figs. 1 and 2, are employed. These attachments are similar in principle to the one previously described, as they each consist of a wire, f', rubber spring, g', washer, h', and burr, i'.

The wire passes through a shoulder-lug, k' , attached by a stout rivet, m , to the frame-plate C. The shoulder-lugs k' , like the shoulder-lugs k of the spring-attachment first described, are allowed a slight movement on their rivets, which permits the wire to accommodate its position to any changed position of the foot-plates, which would not be possible if the shoulder-lugs were rigidly riveted.

In the fig. 2 a portion of the rubber spring and wire is broken away to exhibit the rivets and shoulder-lugs m and k' respectively. In these latter spring-attachments the wires f' pass through slots in the shoulder-lugs k' , instead of holes, as in the shoulder-lugs k , and by means of slots the wires f' are withdrawn to admit of their being unhooked from the holes in the segmental plates Q now about to be described.

On the same rivet, b , that secures the side-plates K to the frame-plates C, as before described, is attached a segmental plate, Q, which is rigidly secured by another rivet at n , which holds it firmly to the side-plate K. This same rivet n also holds the metallic strap P, which latter is allowed a slight movement on the rivet for the better adjustment of the strap G. The lower ends of the wires f' are hooked for the purpose of catching into any one of the holes shown in the segmental plate Q.

By means of the spring-attachments just described, the foot-plates are held in a horizontal position, and by turning the burrs δ' , any required amount of tension can be brought upon the foot of the patient, to bring and retain it in the desired position.

A spring-attachment, as shown in figs. 1, 2, 6, and 7, is for the purpose of producing a continuous tension on the limb, whereby the anchylotic rigidity of the knee-joint may be ameliorated, and eventually overcome by the constant action of the springs. This attachment consists of two bars, R R, sliding on each other with easy contact, and held together by slides o o , which latter have shoulders k'' k'' to serve a similar purpose to those before described, for the straightening-tension is exerted by turning the burrs δ'' . These bars R R lap each other a short distance, and the lower lug is riveted to the upper bar, and upper lug to the lower bar, whereby, when the springs g'' are compressed, the bars are actuated to extend themselves past each other, and thus straighten the frame-plates containing the limb, as one extremity of each bar is pivoted to the curved braces B or D, as shown.

In fig. 1 is shown an auxiliary spring-attachment, similar in principle to one previously described. It comprises the segmental plate Q', rubber spring g''' , hooked wire f''' , washer h''' , and slotted shoulder-lug k''' .

The segmental plate Q' is riveted to the pivot-rivet a at the junction of the upper and lower frame-plates A and C, as shown, and is held rigidly to the frame-plate C by an additional rivet, a' . This auxiliary attachment is to be employed when the knee-joint is so rigid as not to yield appreciably to the tension of the sliding-bar attachment, though either one may be dispensed with in cases where the rigidity of the joint yields to the effect of the other.

On the inner side of the apparatus, that is, at the knee-joint opposite to the segmental plate Q', is a lock-plate, S. This plate is made in the form shown, and is pivoted on the junction-rivet a of the frame-plates A and C.

Holes q' q'' , &c., are made in a segmental arch, and a hole, q , is made in a projection from the said arch. This plate is for locking the apparatus at any desired angle that the holes q' permit, when it is deemed expedient to retain the limb in a certain position, yet without any additional tension on the limb. It also confers strength and rigidity to the apparatus.

When it is desired to remove the tension of the spring-attachments, the lock-plate, which is of steel, and will spring slightly, is slipped around till the hole q catches on the stud r .

When the limb is straight, the opposite hole q' will catch on the stud t , but if the limb is flexed, some one of the other holes g'' g''' will catch on the stud t , and thus the joint of the apparatus will be held firmly at that certain angle. The limb can then be relieved from the constant tension of the spring-attachments before set forth.

In applying and employing this invention, the foot-plates are dropped on their junction-pivot b by removing the wires f' of the spring-attachments from the slots in the shoulder-lugs k' , before described. The wires can then be unhooked from the segmental plates Q, and the foot-plates be permitted to drop down, as before mentioned. The apparatus is then applied to the limb, and the foot-plates raised, and all the straps buckled or buttoned in the manner shown, as firmly as the patient can bear. The burrs of the several spring-attachments are then turned so as to bring a firm and constant pressure to bear upon the joint or joints of the limb, which will eventually accomplish the yielding of the anchylotic rigidity with more or less perfect result, according to the standing of the case.

The horizontal spring-attachment first described is for the purpose of accomplishing the same result in case there be any malformation of the foot, as *talipes vulgaris*, or club-foot. The figs. 1 and 2, which are reverse sides of the same limb with the apparatus applied, exhibit the manner of treating the foot.

The bearing-plate L holds the foot at the middle point, while the plate O, on the movable plate I, bears against the ball of the foot, and actuated by the spring-attachment, as shown, tends to straighten the foot by constant pressure. A bearing-plate, M, bears against the inner end of the heel to keep the latter firm. The strap G is passed first through one ring, l , then downward through the slots j j , then upward through the similar slot, then along by the side of the heel, and crossing over the instep and through the opposite ring l ; then the ends are buckled across the instep, as shown at l' . The application of the strap is nearly identical with that of the heel-strap of a skate.

The drawings clearly set forth the position, form, arrangement, and relative dimensions of the parts of the invention.

The figs. 1 and 2 represent reverse sides of the same limb, with the apparatus applied, but in fig. 1 the limb is not quite straightened. In fig. 2 the limb is represented straight, as the beneficial result of the treatment.

In some of the figures the rubber springs do not abut against the shoulder-lugs as they would when the burrs were screwed up in practice, but are left apart, the better to expose the lugs to view.

Thus, by the above-described pivoted frame and spring-attachments, rigidity of the knee and ankle-joints is overcome, and by means of the pivoted foot plate I and the bearing-plates before described, the inward-fixed curvature of the foot is removed. The framing, in practice, is of steel, and the straps of leather.

Metal springs may be substituted for the rubber springs for the same object, which is to provide an elastic yet firm and constant tension, which shall act efficiently for the end in view, yet permit a slight yielding, whereby the apparatus may be tolerated by the patient.

To the upper extremity of the outer frame-plate A is attached the strap H, before described. This strap passes around the rear part of the thigh, as shown, and is fastened to some fixed point on the opposite side of the patient, for the purpose of exerting a constant tension to turn the whole limb outward, and thus prevent the tendency of the limb to contract an inward and more or less fixed condition, which a long application of the apparatus might in some cases cause.

If, in the incipient stages of ankylosis of the knee and ankle-joints, this principle were resorted to, the disease could be successfully combatted, and with little inconvenience compared to the result.

This invention is particularly desirable for the treatment of children afflicted in the manner set forth in the foregoing, and thousands of adults are debarred from the enjoyment of a more useful and happy life by the absence in surgical practice heretofore of an apparatus as described in the subject-matter of the foregoing.

I am aware that frames and splints somewhat resembling my invention are in daily use in surgical practice, but nothing for the objects set forth in the above has been contemplated in such appliances, or is possible with them.

The apparatus is easily constructed and within the means of all, and can be worn without interfering with such movement as the nature of the rigid joint or joints will permit.

I claim as new, and desire to secure by Letters Patent—

1. The employment of a jointed frame, substantially as shown, at A B D C D', and straps E F G, in combination with any constant spring-tension applied to the said frame for the purpose of straightening it when on the limb, and thereby overcoming any ankylosis rigidly of the knee or ankle-joints of the said limb, all as set forth.

2. The vertically-movable foot-plate J, substantially as shown and described, in combination with its proper spring-attachment, as described, or other equivalent device, and frame-plates C, all as and for the purposes set forth.

3. The laterally-moving foot-plate I, in combination with the bearing-plates L and O and lateral spring-attachment, all substantially as shown and described, and for the purposes set forth.

4. The lock S, substantially as shown and described, or other equivalent device, in combination with the frames A and C, substantially as and for the purpose shown and described.

5. The spring-attachment, consisting of the hooked wire f', shoulder-lugs h', springs g', and burr i, constructed and operated substantially as shown and described, in combination with the foot-plate J and frame-plates C, for the purpose of removing ankylosis, all as set forth.

6. The foot-strap G, or other equivalent device, in combination with the movable foot-plates J and I of an apparatus for straightening feet or lower limbs, all substantially as shown and described, and for the purpose set forth.

7. The elastic strap H, or other equivalent device, applied, substantially as shown and described, to the frame-plate A of an apparatus for removing ankylosis, all as and for the purpose set forth.

8. The metallic strap P, or other equivalent device, in combination with the strap G and movable foot-plates J and I, substantially as and for the purpose shown and described.

The above specification of my invention signed by me, this 15th day of November, 1867.

H. R. ALLEN, M. D.
